GRID FOR ICE TRAYS

Robert Lay Hallock, Larchmont, N. Y.

Application April 2, 1936, Serial No. 72,250

23 Claims. (Cl. 62—108.5)

1

My invention relates to those devices generally termed grids which are used in the production of ice cubes.

The object of my invention is to improve devices of this sort which have for their purpose the removal of ice cubes without running tap water over the tray or ice block. The improvement involves the elimination of rubber in the use of tray or grid while retaining a light-weight structure which can be manipulated with the use of a small amount of force. In order to use a small amount of force I employ a double-walled structure and I form this of metal plates which are made up into a number of separate wafers anchored to a member capable of being bowed. As this member is bowed it moves relative to the division wafers and they move relative to each other so that the ice cubes come off the grid clean with little force. The grid is extremely light but nevertheless sturdy. It is preferably an all-metal grid for a metal tray thereby improving freezing time. Also I aim to provide a grid which is durable and sanitary.

The invention will be understood from the following description taken in conjunction with the accompanying drawings showing the preferred form and forming part of this specification, and of which:

Fig. 1 is a top view of a grid embodying the invention in an ice tray;

Fig. 2 is a vertical longitudinal sectional view taken on the line 2—2 of Fig. 1;

Fig. 3 is a vertical transverse sectional view taken on the line 3—3 of Fig. 2;

Fig. 4 is a vertical longitudinal view taken on line 4—4 of Fig. 3;

Fig. 5 is a sectional view looking down and taken on line 5—5 of Fig. 4;

Fig. 6 is a partial end view of the grid;

Fig. 7 is an elevation of a transverse division member with bail attached forming part of the grid;

Fig. 8 is an elevation of a longitudinal division member forming part of the grid;

Fig. 9 is a vertical sectional view showing operation; and

Fig. 10 is a perspective view of a bail attached to transverse division members of the grid.

The grid includes two spring rods 10 made, for example, of spring steel. Rods 10 extend longitudinally of the grid at the bottom. These rods are adapted to be arched or bowed as shown in Fig. 9 by bending moments applied at the ends of the rods. The rods return to straight or original form on release of force at their ends.

2

At each end of the rods is a rigid member 11. The construction of these members is most clearly shown in Figs. 4 and 6. They may be made of folded plate stampings bulged at the bottom to receive the rods and forked at the top for reception of pivot pins 12. They are rigidly secured to the bow rods 10 as by soldering, brazing or welding.

10 Mounted on pivot pins 12 are levers 13 which may be stamped from sheet steel and which have depending ears through which the pivot pins pass. These levers are so designed that upon being pulled upwardly, as indicated by arrows A in Fig. 2, their opposite ends 14 engage or abut the tray 15 in which the grid is situated to remove the grid from the tray, preferably as described in my U. S. Patent No. 2,009,802 of July 30, 1935.

When the levers 13 have been moved into alignment with end pieces 11 the top ends of the portions of the levers (the lips remote from the hand grasp portions) contact or abut the outside parts of end pieces 11 and further movement causes the parts 11 and 13 to move as one and the spring rods 10 are bowed as shown in Fig. 9.

The grid includes transverse dividing members 16. These members are alike. I will therefore describe one of them. It is made up of 20 two similar plates stamped from very thin stainless steel. Two depressions are stamped in each sheet so that when the sheets are placed together they each touch all around and there is space inwardly of the boundary. The sheets touch on the vertical center-line as will be seen in Fig. 7, so that interior spaces are formed to each side of the center. The boundaries of the sheets are line-welded so that the interior spaces become hermetically sealed. Thus each element, which 30 may be described as a wafer, is a double-walled structure and the opposite walls are yieldable relative to each other. Furthermore the opposite walls are closer together at the bottom than at the top (Fig. 4) and closer at the outside than at the center. We might say that the wafers are tapered downwardly and outwardly.

The transverse dividing members 16 are tied to the rods 10 by bails 17. These bails may be formed of stampings. Each has a central strap portion 18 and is bent to form slots 19 for receiving the bottom edges of the transverse dividing members. The strap portions pass under the rods 10 and the sides are preferably spot-welded to the transverse members as at 20. The 50 bails give rigidity to the transverse members.

Preferably the balls 17 are welded to the transverse members and then slipped onto the rods. These units are loose on the rods.

Extending longitudinally of the rods 10 are longitudinal division members. These are of two kinds. The two at the ends 21 are of one kind and the others 22 are of a different kind. I will first describe one of the parts 22 (see Fig. 8). These are independently made. Each is made up of opposed stamped plates made like the transverse members. They may be made of very thin stainless steel. Depressions are formed in the plates in the stamping operation to provide the double wall structure. The boundaries are line-welded so that the interior space is hermetically sealed. These wafers likewise taper downwardly. At each lower corner is an ear 23. When the parts are assembled these ears slip under the transverse members 16 whereby the wafers 22 are anchored in place. This is the only holding means for wafers 22. The bottom edges, as seen in Fig. 3, lie between rods 10. It will be seen that beneath any transverse member 16 and above any ball 17 are the ears of two longitudinal wafers, the ears being side by side. If desired, the ear on one plate of a longitudinal wafer may be longer than the adjacent ear whereby they dovetail under the transverse members. Wafers 22 are likewise loose with respect to rods 10. Thus rods 10 can bow evenly without constraint and without strain on the wafers. As the rods 10 are bowed upwardly, I might say that the middle bottom parts of wafers 22 move downwardly relative to the rods.

The end wafers 21 differ only in that their edges are made to conform to parts 11. The outer ends are anchored by having ears passing under rivets 24 extending through the sides of parts 11.

In assembling the parts to form the grid, the transverse members 16, with balls 17 attached are slipped onto the rods. The longitudinal members are then placed between the rods and the ears can be readily slipped under the transverse members by spreading the latter somewhat from their final positions. The parts are then brought together and the end pieces, with levers attached are slipped onto the ends of the rods and secured thereto by welding, heading the ends of the rods, caps, or other desired manner.

The use and operation of the grid are as follows:

The grid is placed in the tray and the tray is filled with water. Wafers 16, 21, and 22 divide the water into sections so that, on freezing, ice cubes are formed. To remove the ice cubes, the operator pulls upwardly and outwardly on the levers 13, preferably simultaneously; that is, so that the levers are pulled away from each other. The ends 14 of the levers 13 contact the tray and press the end walls outwardly from the ice block. There is an upward lifting component of force relative to the ice tray and the grid is thus freed from the tray. Preferably the tray is of thin sheet metal so that there is a peeling effect in the loosening of the tray from the ice block.

The operator lifts the grid and continues the separation of the levers from each other and pressure thereagainst. This causes bending moments to be applied to the spring rods 10 as the parts 11 and 13 become in effect a rigid member. The rods are thus bowed upwardly as shown in Fig. 9.

Due to the double wall structure of the division members and their yieldability as the ice expands in forming, the adhesion of the ice to the division members is less than if these parts were solid.

Also a peeling action can take place here. The rods, as they are bowed tend to push the ice pieces upwardly. Due to the downward taper there is no ledge at the bottom to hold the ice pieces. Thus the ice cubes are readily released and completely separated from the division members without cracking or splintering.

Operation of a device made by me, from which the drawings hereto are reproduced, indicates that on bowing rods 10, the ice pieces are first released from the transverse members. Separation starts from the top and there is a progressive peeling downwardly along the lateral walls of the transverse members. While this is going on, the ice pieces remain adhering to the center longitudinal wafers. It seems that the portions of rods 10 stay straight under the center parts of the ice pieces and curve at the places where the rods pass through the balls. This sets up a strain in the rods which may be considered an accumulated force. When the release from the transverse members is completed, the upward strain of the rod against the ice pieces causes a quick release at the center wafers. I have found this release to be more effective with this construction than when the rods are tied to the center wafers at their respective centers.

It will be obvious that variations may be made in the structure.

What I claim is:

1. A grid including a spring member adapted to be bowed, transverse members held with respect to said spring member, and longitudinal members between the transverse members held with respect to the other members only at their longitudinal ends adjacent the transverse members.
2. A grid as defined in claim 1 including common members for tying the transverse and longitudinal members to the spring member.
3. A grid for refrigerators including a plurality of aligned vertical longitudinal dividing members, separate transverse dividing members disposed between the longitudinal members, and means to tie the longitudinal members to the transverse members at the lower corners of the longitudinal members, the vertical edges of the longitudinal members being otherwise free for movement relative to the transverse members and the lower edges of the longitudinal members being free of the tying means at their lower edges.
4. A grid for a refrigerator including a series of double-walled transverse dividing members, a series of double-walled longitudinal dividing members, said members being separately hermetically sealed, the bottom corners of the longitudinal members being tied to the transverse members, the transverse and longitudinal members being otherwise separable, and means to arch the grid to spread the separable portions of the dividing members.
5. A grid for an ice tray including a U-shaped spring member, means to spread the legs of the U and curve the bottom, and wall members mounted on the U bottom to flare when the legs are spread.
6. A grid including a longitudinal member adapted to be bowed, a lever handle pivotally associated with said member and adapted first for releasing the grid from a tray and then for bowing said member, said lever handle being movable through a given arc, and a part attached to and movable in correspondence with the lever handle having a first abutment engageable with a tray at a given point in the lever arc for release of the grid from the tray and a second abutment

engageable with another part of the grid at a further given point in the arc of travel of the lever handle to cause the grid to be bowed.

7. A removable grid for an ice tray having a bottom and side walls, said grid being capable of being bowed and including a longitudinal partition and transverse partitions and relatively rigid end pieces, and levers pivoted at the upper ends of said rigid end pieces and operative upon movement thereof to lift the grid from the tray, said levers also having lips engageable with parts of the grid so related to the pivot points of the levers that the levers are operative upon limited movement thereof in the same direction to exert a bending moment in said grid after the latter is lifted from the tray.

8. A removable grid for an ice tray comprising structure adapted to be bowed and including a longitudinal partition and transverse partitions forming a plurality of ice cube compartments, and a lever pivotally associated with said longitudinal partition and operative to engage a part of the tray to lift the grid from the tray with the ice cubes attached thereto, said lever also having a lip engageable with a part of the grid so related to the pivot point of the lever that the lever is operative upon further movement in the same direction to bow said grid and free the ice cubes from said transverse and longitudinal partitions.

9. A removable grid for an ice tray including a longitudinal partition and transverse partitions, and a lever pivoted at one end of said grid and operative upon movement thereof to lift the grid from the tray, said lever also being operative upon continued limited movement thereof in the same direction to exert a bending moment in said grid after the latter is lifted from the tray, and said grid being so constructed and arranged that it is rigid when said lever is operated to lift the grid from the tray and flexible when said lever is operated to exert said bending moment.

10. Ice forming apparatus including a tray, a distortable grid, and levers pivoted on said grid at opposite upper end parts thereof and having hand-grasp portions and opposite extensions, said extensions being constructed and arranged to contact the tray on moving the levers and to contact the grid on further movement of the levers at places so related to the pivot points of the levers that force couples can be applied at opposite ends of the grid to distort the grid.

11. A grid for refrigerators including a plurality of aligned vertical longitudinal dividing members, separate transverse dividing members disposed between the longitudinal members, and means for holding said members in position relative to each other including an underlying longitudinal member held to said members adjacent the ends of the lower edges of the longitudinal dividing members and free to move relative to intermediate parts of said lower edges, said underlying member providing recesses in alignment with the longitudinal dividing members.

12. A grid as defined by claim 11 in which the longitudinal member is relatively narrow and is made of spring material and is adapted to be bowed so that the longitudinal dividing members enter the recesses on bowing.

13. A removable grid for an ice tray having a bottom and side walls, said grid including individual longitudinal and transverse partitions held together so as to be relatively movable, and mechanism including a lever pivoted at an upper part of said grid and movable through an arc, said mechanism including a part adapted, upon move-

ment of the lever to a predetermined point in its arc of travel, to abut the tray and operative upon movement thereof to release the grid from the tray, said mechanism also including a movable part adapted, upon further movement of the lever to a second predetermined point in its arc of travel, to abut a part of the grid and being operative upon said last-named abutment to cause relative movement of said partitions after the grid is released from the tray.

14. Ice forming apparatus including a tray, a distortable grid including separate compartment forming members and a longitudinal member for holding the compartment forming members while permitting relative movement therebetween, said longitudinal member having a part positioned at an upper part of the grid, and leverage mechanism pivotally mounted on said longitudinal member at the upper part of the grid and constructed and arranged to cause force application between the tray and grid for separating them and constructed and arranged to cause force application between spaced points of the longitudinal member to exert a distorting force in the grid.

15. A grid for refrigerators including a plurality of aligned vertical longitudinal dividing members, separate transverse dividing members disposed between the longitudinal members, and means for holding said members in position relative to each other including longitudinally extending distortable means held to said members adjacent the ends of edges of the longitudinal dividing members and free to move relative to intermediate parts of said lower edges, said distortable means being so constructed and arranged relative to said members that, on distortion of said means, parts thereof intermediate transverse members have substantial movement toward center portions of the longitudinal members without interference by the longitudinal members.

16. A grid for refrigerators including a plurality of aligned vertical longitudinal dividing members, separate transverse dividing members disposed between the longitudinal members, means for holding said members in position relative to each other including longitudinally extending distortable means held to said members adjacent the ends of edges of the longitudinal dividing members and free to move relative to intermediate parts of said lower edges, and members at the ends of said holding means for distorting the same, said distortable means being so constructed and arranged relative to said dividing members that, on distortion of said means, parts thereof intermediate transverse members have substantial movement toward center portions of the longitudinal members without contacting the longitudinal members.

17. A grid for refrigerators including a plurality of aligned vertical longitudinal dividing members, separate transverse dividing members disposed between the longitudinal members, and means for holding said members in position relative to each other including an underlying longitudinal member held to said members adjacent the ends of the lower edges of the longitudinal dividing members and free to move relative to intermediate parts of said lower edges, said underlying member being so constructed and arranged relative to the longitudinal and transverse dividing members that, on movement of the underlying member, parts thereof intermediate transverse members have substantial upward movement without interference by longitudinal members.

18. A grid for refrigerators including a plurality of aligned vertical longitudinal dividing members, separate transverse dividing members disposed between the longitudinal members, means for holding said members in position relative to each other including an underlying longitudinal resilient member adapted to be bowed held to said dividing members adjacent the ends of the lower edges of the longitudinal dividing members and free to move relative to intermediate parts of said lower edges and extensions at the ends of said resilient member for bowing the same, said underlying member being so constructed and arranged relative to the transverse and longitudinal dividing members that, on bowing the underlying member, parts thereof intermediate transverse members have substantial upward movement without interference by longitudinal members.

19. A grid including a resilient member adapted to be bowed, transverse members held with respect to said resilient member, and longitudinal members between the transverse members and having ears at their ends along a longitudinal edge thereof which extend through the planes of said transverse members to facilitate holding said longitudinal members in position while permitting relative movement between said longitudinal members and said transverse members.

20. A grid for refrigerators including a plurality of aligned vertical longitudinal dividing members, separate transverse dividing members disposed between said longitudinal members, and means operatively connecting the corners of said longitudinal members and said transverse members along a longitudinal edge of said longitudinal members, the vertical edges of said longitudinal members being otherwise free for movement relative to said transverse members and said longitudinal edge of said longitudinal members being free of said connecting means.

21. A distortable grid removably fitting in an ice tray for freezing ice and including separate

5 compartment forming members and a longitudinal member for holding the compartment forming members while permitting relative movement therebetween, and mechanism including one or more members mounted at an upper portion of said grid and constructed and arranged to be movable from a plane parallel to the upper longitudinal edge of said compartment forming members to a vertically extending position and then 10 operable in the latter position to cause force application in opposite directions between spaced points of the longitudinal member to exert a distorting force to facilitate breaking of the ice bond.

15 22. In a grid for ice trays, a spring member, wall pieces mounted on said spring member, and other wall pieces held between the spring member and the first-mentioned wall pieces whereby the first-mentioned wall pieces hold the other 20 wall pieces to said spring member.

25 23. In a grid for ice trays, a slotted longitudinal spring member, longitudinal wall pieces loosely mounted to in part project into the slotting of the longitudinal member, and transverse wall pieces directly mounted on the spring member and acting to position the longitudinal wall pieces.
